UNITED STATES PATENT OFFICE.

HAROLD F. ELLIOTT, OF PALO ALTO, CALIFORNIA, ASSIGNOR, BY DIRECT AND MESNE ASSIGNMENTS, TO VICTOR TALKING MACHINE COMPANY, OF CAMDEN, NEW JERSEY, A CORPORATION OF NEW JERSEY.

HIGH-FREQUENCY TRANSFORMER.

Application filed September 17, 1927. Serial No. 220,151.

This invention relates to radio signaling systems, and especially to radio frequency transformers utilized in connection therewith.

5 In radio receivers, it is now quite common to utilize one or more radio frequency amplifier stages, whereby the signaling impulses are first amplified, as by thermionic amplifiers, before detection. Radio frequency coils or transformers are used to pass the impulses from one stage to the next stage.

10 It is one of the objects of my invention to improve in general, this type of coil or transformer.

15 When electronic emission devices are utilized as the amplifiers, certain complications occur which will now be discussed. Such amplifiers usually include a source of 20 electrons, such as a filament heated by the passage of electric current through it, and a plate or anode to which the electrons are attracted. The plate is kept at a potential positive with respect to the filament as by 25 a battery or the like connected between the electrodes. The space current formed by the electrons can be controlled by a third electrode or grid placed in the tube, by controlling the potential difference between the 30 grid and the filament. It has been found that small changes in this potential difference cause much larger corresponding changes in the space current; and thus an amplifying effect is produced. The variations 35 in the space current are caused to affect the current flow in the output circuit connecting the filament and plate, and this current in turn can serve to impress varying potentials upon a grid of a succeeding 40 amplifier.

It has been found that such an amplifier has a tendency to become unstable, due to the parasitic capacity effect between the grid and plate, and the conditions of the 45 circuits connected to these electrodes. For overcoming this instability, a neutralizing circuit can be used; and such a neutralizing circuit involves the addition of a third winding on the coupling transformer, either as 50 a primary or as a secondary.

It is another object of my invention to provide a novel and compact transformer in which such a winding can be easily included.

Such a transformer is described and 55 claimed in a prior application filed March 11, 1927, in my name, having Serial No. 174,475, and entitled "System of neutralization." My present application is a continuation in part of said prior application. 60

In order to secure the best results with such amplifier systems, it is essential to reduce as much as possible, all sources of inefficiency, as for example, the energy losses in the dielectric material between conductors 65 or windings on the transformer. With the aid of my invention, such dielectric losses are reduced to a low value.

It is also well-known that in order to secure undistorted and stable amplification, the 70 radio frequency circuits should be shielded from one another and from stray effects. It is another object of my invention to produce a compact transformer that can be arranged in a shield without any difficulty. 75

My invention possesses many other advantages, and has other objects which may be made more easily apparent from a consideration of one embodiment of my invention. For this purpose I have shown a form 80 in the drawings accompanying and forming part of the present specification. I shall now proceed to describe this form in detail, which illustrates the general principles of my invention; but it is to be understood 85 that this detailed description is not to be taken in a limiting sense, since the scope of my invention is best defined by the appended claims.

Referring to the drawings:

Figure 1 is a sectional view of a transformer embodying my invention and shown as supported on a frame;

Fig. 2 is a front elevation of one of the transformer frames;

Fig. 3 is a sectional view thereof;

Fig. 4 is a plan view showing a transformer disposed in a shield;

Figs. 5 and 6 are detailed front and side views of one of the parts making up the 100 transformer structure;

Figs. 7 and 8 are diagrammatic views illustrating the mode of wiring the transformer; and

Fig. 9 is a wiring diagram illustrating one 105 way in which the transformer can be used.

In Fig. 9 I show a radio frequency thermionic amplifier 11 to which radio fre-

quency impulses are passed, and which passes the amplified impulses to further amplifiers and detector, indicated by rectangle 12. The impulses to be amplified are shown 5 as first passed to a primary winding 13 of a transformer 14, by the aid of the incoming leads 15, 16, which can connect to any desired form of pick-up system. A secondary coil 17 connects at its opposite ends respectively to the control electrode or grid 18, and to the electron emitting electrode or filament 19, as by the aid of ground connections 20 and 21. This filament is shown as heated by an adjustable current from battery 22. The output circuit includes plate or anode 23, a primary coil 24, source of positive potential 25, and filament 19.

In order to neutralize the parasitic capacity coupling between grid 18 and plate 20 23, a neutralizing circuit can be used, such for example as that connecting plate 23 and ground 20, and including the neutralizing condenser 26 and a coil 27 closely coupled to coil 17. If coil 27 has the same inductance as coil 17, and if condenser 26 has the same value as the parasitic capacity, then it can be shown that by proper connection of coil 27, the disturbing electromotive forces produced in coil 17 due to the parasitic 25 coupling are substantially entirely neutralized by the electromotive forces induced in it by coil 27. The theory of such neutralization is now well-known, and needs no further elucidation.

30 In order to tune the system to a definite frequency, a variable condenser 28 can be connected across both coils 17 and 27. Furthermore, a metallic shield 29 is indicated as encompassing the transformer 14 and condenser 28.

40 The amplified impulses passed to primary 24 are in turn passed to a succeeding stage that can be entirely similar to the one just described. Thus secondary coil 30 and neutralizing coil 31 are shown as coupled to coil 24, and are bridged by variable condenser 32. These parts correspond to parts 45 17, 27 and 28 of the first stage, and they can be used to affect the succeeding stages represented by rectangle 12. As many stages can be thus cascaded as desired. Ultimately, a 50 detector is utilized, and if desired, one or more stages of audio frequency amplifiers. Finally the amplified and detected impulses 55 are passed to a translating device such as phones 33. A shield 34 is also shown, encompassing the transformer and condenser 32.

60 In this type of neutralization, it is essential to couple closely the secondaries 17 and 27, as well as secondaries 30 and 31; and in fact in such a way that the leakage inductance of both coils be small enough to provide a very high natural period determined 65 by this leakage and the disturbed capacity

of the system. Especially should this period be higher than the natural period of the output circuit, determined by its distributed capacity and leakage inductance. With the aid of my invention, the close coupling of 70 the two windings 17 and 27, or of 30 and 31 can be very easily accomplished, as will be evident from the following description of the transformer details.

The transformer structure 14 is shown in 75 detail in Figs. 1 to 8. It is shown as supported on a metallic frame 35. There is a right and left support 36 and 37 made from insulation, such as molded bakelite. The left support 37 is shown in detail in Figs. 2 80 and 3, and since both supports are quite similar, the description of one of them will be sufficient to serve as a description of both.

85 Each support has a base portion 38, adapted to be fastened to the frame 35 as by screw 39. It further has a pair of hollow lugs 40 passing through apertures in frame 35. These lugs serve a dual purpose: to position the supports properly on frame 35, as well as to permit connections to pass 90 from the transformer 14 through frame 35 and below it. Each support furthermore has an upright thin body 41 which is provided with a flange 42 for lending rigidity to the structure. It also has a circular 95 flange 43 that serves as a support for a winding, when the two supported are fastened together.

100 At the center of the support, there is a boss 44, provided with an aperture 45 whereby a bolt 46 can be passed through both supports for holding them together. The bosses 44 are held spaced apart by a series of circular projections 47 spaced annularly of boss 44, and having their centers at about the 105 periphery of the boss. Vanes or ribs 48 connect the boss with flange 43. Furthermore, flange 49 is provided around the bolt aperture 45 to enable the transformer to be held in a chuck for winding.

110 With the two supports 36 and 37 fastened together as shown in Fig. 1, the flanges 43 are separated by a considerable distance; and this space between the flanges can be further split up into two parts by a disc 50 115 shown in detail in Figs. 5 and 6. This disc is made from insulation material and is cut away as shown at 51 to provide as little dielectric as possible. It too has an aperture 52 for the passage of bolt 46 and is 120 firmly clamped between bosses 44. The projections 47 enter between the spokes 53 of the disc.

125 The two secondaries 17 and 27 can be wound in pancake form on opposite sides of disc 50, and between it and the supports 36 and 37. The spokes 53 and ribs 48 serve to maintain these coils in proper flat form. The primary winding 13 can be disposed over the flanges 43, but separated from them 130

5 by a few layers of insulation 54, such as varnished cambric. It is seen that as much dielectric material is removed from the field of the coils as possible, to reduce the dielectric loss, while yet maintaining a rigid structure.

10 For ordinary broadcast reception, coil 13 can be wound with about forty-two turns, and each of the coils 17, 27 with about forty-five turns. The size of the wires is exaggerated in the drawings, whereby the turns appear to be less in number than these values.

15 In Fig. 4 I show the arrangement of the transformer 14 and condenser 28 in its shield 29, which is shown as oval in form. The condenser 28 is indicated as one having a pair of electrodes pivoted for movement about spaced axes and moved by operation 20 of links 55, which extend through an opening in shield 29.

25 In order to explain the mode of wiring the transformer, the diagrams of Figs. 7 and 8 are included. Fig. 7 is a view taken from the left of Fig. 1; and Fig. 8 is a view 30 taken from the right thereof. In Fig. 7, coil 27 is shown as having its inner terminal brought out through aperture 56 to the outside of support 36. The lead 57 is then, for support, looped in and out of apertures 58 and 59, and is finally soldered or otherwise connected to a soldering lug 60 that 35 is partly embedded in support 36. From this lug extends wire 61 through one of the lugs 40 for connecting to the neutralizing condenser 26. To the lug 60 is also connected one terminal of condenser 28, as indicated by connection 62 (Fig. 4).

40 The outer terminal of coil 27 passes to the outside of support 36 by way of aperture 63, and a lead 64 connects it to a ground connection. The other secondary 17 is wound in a direction opposite that of coil 27; its inner terminal extends through aperture 45 65 in support 37, and is soldered to a soldering lug 66 carried by said support. Connection 67 extends from lug 66 and through the boss 40 to the grid 18. The outer terminal of coil 17 extends through aperture 50 68 in support 36 to connect to the common 70 grounded center lead 64.

75 The connections for primary coil 13 can be best explained by the aid of Fig. 8. The terminals of this coil extend through apertures 69 and 70 respectively, in support 37, and thence they proceed through the apertured boss 40, to the preceding stage of amplification.

80 Of course, coils 24, 30 and 31 for the next stage, can be similarly supported and connected; and all further stages can be equivalently constructed.

85 It is to be noted that the outer terminals of coils 17 and 27 are grounded; this serves

90 to produce a grounded electrostatic shield 65 between the primary and secondary coils. Furthermore, due to this feature, and since the primary 13 is symmetrical with respect to the secondaries, which are themselves 95 symmetrical both electrically and mechanically, there is very little capacity coupling 100 between primary 13 and either of the other coils 17 and 27. This is of the highest importance, for if there were any substantial coupling, there would be a path formed for 105 feed-back energy between the detector output back through all the preceding stages to the first stage, and this would result in material regeneration and instability.

110 The advantages therefore, of this design 80 involve a definite relative arrangement of the coils to ensure close coupling, elimination of material feed back, and of stray capacity and leakage inductance. All these 115 are essential for stability; and the symmetrical arrangement also ensures that the neutralization will be effective for the entire range of the system.

I claim:

120 1. A radio frequency transformer including a support made from insulation material, a plurality of coils supported therein, said support having a plurality of hollow lugs arranged to extend through a wall, and connections for the coils passing 125 through said lugs.

130 2. In a radio frequency transformer, a pair of supports of insulation material, each of said supports having a flange, means for fastening the supports together so that the 100 flanges are coaxial but spaced apart, each of said supports also having a series of radial ribs extending between the flange and the common axis of the flanges, a pancake coil structure disposed between the supports 105 and supported by said ribs, and a coil wound on the flanges.

140 3. In a radio frequency transformer, a pair of closely spaced equal pancake coils, a ground connection to the outer terminal of 110 each of said coils, and a cylindrical coil coaxial with the pancake coils and symmetrically placed thereover.

145 4. In a radio frequency coil structure, a pair of pancake coils, and means for supporting said coils close together and for reducing the dielectric loss, comprising insulation supports having spaced radial members of insulation material, one of said supports being interposed between the coils, 120 and the others respectively on the outside surfaces of the coils.

150 5. In a radio frequency transformer, a pair of insulation supports, each having a circular boss, as well as a series of projections extending beyond the boss and arranged to be in engagement when the supports are fastened together, a spoked disc

of insulation material held between the bosses, pancake coils disposed respectively between each of the supports and the disc, and a cylindrical coil disposed over the pancake coils and supported on said supports.

6. A coil support for high frequency coils, comprising a pair of flanged supports made from insulation material, means for fastening said supports together, each of said supports having a boss, said bosses being concentric when the supports are fastened together, and coaxial with the flanges, each of said supports also having a face that is opposed to the face on the other support when the supports are fastened together, and a disc clamped between the bosses and defining a pair of narrow spaces between it and the flanged supports.

7. The combination as set forth in claim 6, with the limitation that the supports and the disc are so formed that only a small por-

tion of the insulation material of the disc and supports face each other.

8. The combination as set forth in claim 6, with the limitation that the disc is cut away to form a spoked disc, and the supports present raised radial ribs to the adjacent surfaces.

9. A support for a radio frequency coil, comprising a base, a wall extending from the base, a flange extending from the wall, a boss concentric with the flange, and projections extending from the bottom of the base for spacing the support with respect to apertures accommodating said projections.

10. The structure as set forth in claim 9, in which radial ribs extend between the boss and the concentric flange.

In testimony whereof I have hereunto set my hand.

HAROLD F. ELLIOTT.
